UNITED STATES PATENT OFFICE

2,054,754

CONTAINER AND HEAT INSULATING MEANS THEREFOR

John L. Kellogg, Chicago, Ill., assignor to Helen L. Kellogg, Chicago, Ill.

Application October 22, 1934, Serial No. 749,412

2 Claims. (Cl. 220—9)

This invention relates to improvements in the construction of containers which are used for holding fluids such as malt beverages, milk and other liquids which must be maintained at comparatively low temperatures during shipment and storage preparatory to consumption.

One of the important objects of the invention is to provide a container for the purpose specified having spaced inner and outer walls between which there is interposed a mass of non-conductive heat insulating material, together with a body of heat reflective material, the latter being in the form of a sheet which is interposed between the insulating mass and at least one of the container walls.

Another object of the invention is to provide a double walled container of the type specified, having between the walls thereof a mass of non-conductive heat insulating material which has been molded to a shape substantially filling the space between the walls whereby to hold the latter in proper spaced relation, and in combination with said molded mass, a body of heat reflective material which is disposed in the form of a thin sheet between said mass and either one or both of the container walls.

A further object of the invention is to provide a container of the character referred to which may be made cheaply, and which will be sufficiently rugged to be useful in the shipping and storage of beverages such as beer, milk and the like.

Other objects and advantages of the invention will be apparent from the following detailed description, taken in connection with the accompanying drawings wherein I have shown the preferred form in which I have thus far contemplated applying the principles of the invention.

Referring to the drawings:

Fig. 1 is a vertical section through a double walled container constructed in accordance with the invention; and

Fig. 2 is a broken vertical section through the container, the view showing the opposite halves of the outer receptacle partially removed from the assembled position to illustrate the manner in which the insulating material is incorporated between the inner and outer receptacle walls.

Referring to the drawings in detail, the reference numeral 3 designates generally an inner sheet metal receptacle consisting of a top head wall 4, a bottom head wall 5, and a side wall 6 which is joined to head walls 4 and 5 to form a closed barrel-shaped receptacle. These walls 55 are ordinarily made of sheet metal, the upper

wall 4 being formed by a stamping operation and the side wall 6 being formed by a stamping operation.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

Fig. 1 shows the receptacle 3 joined to a side wall 8 which is formed of sheet metal and which is joined to a head wall 9 and a side wall 10.

Fig. 2 shows the receptacle 3 joined to a side wall 8 which is formed of sheet metal and which is joined to a head wall 9 and a side wall 10.

contact between head ring 22 and wall 9 is thus prevented through the provision of insulating collar 23 and washer 21, thereby eliminating direct conduction of heat from wall 9 through ring 5 22 to wall 4.

In accordance with my invention, means is provided for insulating inner receptacle 3 to prevent conduction and radiation of heat thereto through outer receptacle 8. My experiments have shown 10 that provision of a mass of non-conductive heat insulating material in the space between the inner and outer receptacle walls does not serve to completely prevent transmission of heat to the inner receptacle, this being due to the fact that 15 a very substantial amount of heat is transmitted by radiation and conductance to the walls of the inner receptacle. I have discovered, however, that by using a reflective insulating material, in combination with a mass of non-conductive 20 insulating material and by eliminating all metallic connections between the inner receptacle and the outer receptacle, I am able to almost completely prevent transmission of heat to the walls of the inner receptacle.

25 In the embodiment of the invention shown in the drawings I provide between the receptacle walls a mass of non-conductive heat insulating material 31, which substantially fills the space between side walls 6 and 11, as well as the space 30 between top head walls 4 and 9, and bottom head walls 5 and 10. Any suitable non-conductive heat insulating material such as cork, fibre, felt, hair, magnesia and mineral wool, may be used for this purpose. This body of insulating material 31 serves both as an insulating medium, 35 and also as a means for rigidly holding the receptacles in proper spaced relation. I have found that the latter function may be best performed by molding the insulating material to the desired 40 shape. If necessary, a small amount of a suitable binder, such as glue, may be incorporated with the mass to render it suitable for molding. In the molding operation the mass is compressed to give it the necessary density and strength to 45 serve as a spacer for preventing contact between the inner and outer receptacles. By using a molded insulator it is unnecessary to provide reinforcing and spacing ribs to hold the two receptacles in proper spaced relation. The elimination of such ribs, of course, avoids direct metallic contact between the inner and outer receptacle walls, and thereby minimizes conduction of heat to the inner receptacle.

50 The reflective heat insulating material which is used in combination with the non-conductive material 31 comprises a thin layer or sheet of polished metal which is interposed between the mass 31 and the adjacent walls of receptacles 3 and 8. A sheet of metal foil 32 is interposed between the mass 31 and walls 9, 10 and 11 of the outer receptacle, and a similar sheet of metal foil 33 is interposed between mass 31 and walls 4, 5 and 6 of the inner receptacle. Any polished metal foil or thin sheet metal having heat reflective properties may be used to form the sheets 55 32 and 33. I prefer to use the reflective sheets between the mass 31 and the walls of both the inner and outer receptacles, however, if preferred, one or the other of the sheets 32, 33 may

be omitted, the insulator being employed on only one side of the mass 31. Also, it may be desired to employ a thin sheet of reflective material in the form of an electro-plate deposited either on the inner surface of the walls of the outer receptacle or on the outer surface of the walls of the inner receptacle, and the use of a reflective material in this manner is considered to be fully within the scope of the invention.

5 In Fig. 2 I have shown the sequence of steps or operations involved in building up the double walled unit from the half sections of the inner and outer receptacles. The inner receptacle 3 is first made up by welding together the opposite halves thereof as indicated at 7, after which 10 bung rings 14 and 22 are placed in position and welded. The opposite halves of the mass of insulating material 31, which have been preliminarily molded to shape, and to which sheets 32 and 33 of reflective insulator have been applied, 15 are then placed in position over the opposite ends of the inner receptacle. These molded sections are formed with suitable openings 34 and 35 for receiving rings 14 and 22 respectively. The half-sections of the outer receptacle 8 are then placed 20 over the opposed halves of the insulating mass 31, and the composite half sections are then compressed or forced together over the ends of the inner receptacle, insulation collars 17 and 23 having 25 been preliminarily placed in position on rings 14 and 22, respectively. After the parts have come into abutting relation the opposite halves 30 of the outer receptacle are welded together as indicated at 12, and washers 21 and 28 are then 35 welded to the outer ends of rings 14 and 22, respectively, to complete the unit.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. A tap structure for a double walled receptacle comprising a tubular body secured to the wall of the inner receptacle around the tap opening therein, said body projecting from the inner receptacle through the wall of the outer receptacle and having a perimetrical channel formed 45 therein for receiving the marginal walls of the tap opening in the outer receptacle, and a mass 50 of heat insulating material disposed in said channel between said body and the walls of the outer container.

2. In a double walled sheet metal receptacle, a tap structure comprising a metal sleeve secured at its inner end to the wall of the inner receptacle around the tap opening therein, the outer end of said sleeve projecting through the wall of the outer receptacle and the body of said sleeve being cut away to receive the marginal walls of the tap opening in the outer container, and a body of heat insulating material disposed in the cut away portion of said sleeve, said material being arranged to prevent all metallic contact between said sleeve and the adjacent wall of the outer container.
